[57] ABSTRACT

A body is provided and defines an elongated substan-

tially straight groove extending along and opening outwardly of one side of the body. Abutment structure is supported from the body in registry with one end of the groove for adjustable shifting in a direction generally paralleling the groove and is adapted to have the pointed end of a needle seated in the groove abutted thereagainst. A second elongated and substantially straight groove is formed in the same side of the body at generally right angles relative to the first groove and intersects with the latter intermediate its opposite ends. The second groove is adapted to seatingly receive a length of sewing thread therein and the body supports an elongated blade portion having one end thereof shiftable along a path disposed normal to a plane containing the grooves and intersecting with the center lines of the grooves. The blade end is of a cross-sectional shape to be received through the eye of a sewing machine needle seated in the first groove and having its point abutted against the abutment structure for the purpose of projecting a length of sewing thread disposed in the second groove through the eye of the needle, the adjustable abutment structure being provided to establish proper longitudinal displacement of the needle relative to the body in a manner such that the eye of the needle is registered with the path along which the blade is projected.

Fig. 3

SEWING MACHINE NEEDLE THREADER

BACKGROUND OF THE INVENTION

Sewing machine needle threading devices have been heretofore designed for the purpose of facilitating the threading of a sewing machine needle. Examples of these previously devised sewing machine needle threading devices are disclosed in U.S. Pat. Nos. 2,006,185 to S. Sidler, dated June 25, 1935, 2,476,872 to J. N. Jamo, dated July 19, 1949, 2,507,370 to A. E. Edwards, dated May 9, 1950, 2,483,595 to C. U. Olson, date Oct. 4, 1949 and 2,525,034 to J. N. Jamo, dated Oct. 10, 1950.

However, these previously known needle threading devices have not included readily infinitely variable means whereby the needle threading devices may be adjusted to compensate for different makes, sizes and types of sewing machine needles. As a result, most of these previous sewing machine needle threading devices are preset to be utilized in conjunction with a given needle or must be adjusted in a reasonably complicated manner in order to function properly in connection with needles of various sizes.

BRIEF DESCRIPTION OF THE INVENTION

The needle threader of the instant invention includes a body having a first laterally opening groove formed therein for seatingly receiving a needle extending longitudinally of the groove. The body includes abutment structure registered with one end of the groove and adjustably shiftable along the center line of the groove so as to define an adjustable abutment for precisely longitudinally positioning an associated needle in the groove. The body includes a second groove disposed at generally right angles to the first groove and formed in the same side of the body and which intersects with the first groove. The second groove is provided to seatingly receive a length of sewing thread extending longitudinally therealong and a blade is supported from the body and includes a thin terminal end projectable through the intersecting midportions of the grooves along a path disposed substantially normal to a plane in which the grooves are disposed, the terminal end of the blade being projectable through the eye portion of a needle registered with the intersecting mid-portions of the grooves and the path along which the terminal end of the blade is shiftable.

The main object of this invention is to provide a needle threader which may be quickly and efficiently utilized to thread the needle of a sewing machine.

Another object of this invention is to provide a needle threader which is readily infinitely adjustable so as to adapt the threader to be utilized in conjunction with different models and sizes of sewing machine needles.

Yet another important object of this invention is to provide a needle threader in accordance with the preceding objects and which may be utilized in conjunction with different types of sewing threads.

A final object of this invention to be specifically enumerated herein is to provide a needle threader which will conform to conventional forms of manufacture, be of simple construction and easy to use so as to provide a device that will be economically feasible, long lasting and relatively trouble free in operation.

These together with other objects and advantages which will become subsequently apparent reside in the details of construction and operation as more fully

hereinafter described and claimed, reference being had to the accompanying drawings forming a part hereof, wherein like numerals refer to like parts throughout.

BRIEF DESCRIPTION OF THE DRAWINGS

FIG. 1 is a perspective view of the needle threader of the instant invention;

FIG. 2 is an enlarged horizontal sectional view taken substantially upon the plane indicated by the section line 2-2 of FIG. 1;

FIG. 3 is a longitudinal vertical sectional view taken substantially upon the plane indicated by the section line 3-3 of FIG. 2; and

FIG. 4 is a fragmentary perspective view illustrating the manner in which the projectable slide portion of the needle threader is utilized to project an associated length of thread through the eye of a sewing machine needle with which the invention is being used.

DETAILED DESCRIPTION OF THE INVENTION

Referring now more specifically to the drawings, the numeral 10 generally designates the needle threader of the instant invention. The threader 10 comprises an elongated body 12 having a longitudinal slot 14 formed therethrough and in which a blade member 16 is longitudinally reciprocal. The slot 16 includes intermediate and forward successively reduced height portions 18 and 20, respectively, and the blade member 16 includes a longitudinal transverse slot 22 through which a transverse pin 24 secured through the body 12 passes. The pin 24 defines, in conjunction with the opposite ends of the slot 22, limits of longitudinal shifting of the blade member 16.

The body 12 includes a rear end 26 through which the rear end portion 28 of the blade member 15 projects. The rear terminal end of the blade portion is transversely enlarged as at 30 to define a finger-engageable knob for transferring longitudinal thrust to the blade member 16 so as to shift the latter forwardly relative to the body 12.

The blade member 16 includes a reduced height portion 32 which projects into the reduced height portion 18 of the slot 14 and a forward terminal end further reduced height portion 34 which is projectable through the reduced height portion 20 of the slot 14. Also, the body 12 includes a rearwardly opening internal blind bore 36 whose forward end is closed and whose rear end opens into the forward extremity of the full height portion of the slot 14. A compression spring 38 is seated in the blind bore 36 at its forward end and the rear end of the compression spring 38 bears against the shoulder surface 40 of the blade member 16 defined at the rearmost extremity of the reduced height portion 32 of the blade member 16, the spring 38 serving to yieldingly bias the blade member 16 to its rearmost position in the slot 14.

The forward end 42 of the body 12 includes a first upstanding generally straight and forwardly laterally outwardly opening groove 44 as well as a second horizontal transverse groove 46 which opens laterally outwardly of the forward end of the body 12 and includes a mid-portion intersecting with the lower end portion of the groove 44.

The forward second reduced portion 20 of the slot 14 opens through the intersecting portions of the grooves 44 and 46 and the mid-portion 48 of an elongated lever 50 extending longitudinally of the underside of the

body 12 is rockably supported from the under portion of the body 12 intermediate its opposite ends by means of a fastener 51 threaded into a downwardly opening threaded blind bore 52 formed in the bottom of the body. The forward terminal end 54 of the lever 50 is disposed in registry with the lower end of the groove 44 and is adapted to have the pointed lower terminal end 56 of a sewing machine needle 58 disposed in and extending along the groove 44 abutted thereagainst with the eye 60 of the needle 58 registered with the forward extremity of the forwardmost reduced height portion 20 of the slot 14 through which the forward terminal end 34 of the blade member 16 is projectable. The cross-sectional shape of the forward terminal end 34 of the blade member 16 is such to be readily passed through the eye 60 of the needle 58 and the forward end face of the terminal end 34 is transversely notched as at 62 to seatingly engage sewing machine thread 64 extending through the groove 46. In this manner, the sewing machine thread 64 may be readily projected through the eye 60 of the needle 58 upon forward displacement of the blade member 16.

A compression spring 66 has one end thereof seated in a downwardly opening blind bore formed in the body 12 and the other end bearing against the upper side of the rear end portion of the lever 50. Also, an internally threaded sleeve 68 having a finger engageable diametrically enlarged head 70 on its upper end is rotatably and slidably received in a vertical bore 72 formed through the body 12 to one side of the slot 14. A headed shank-type screw 74 has its threaded shank portion 76 rotatably and threadably engaged in the lower end of the sleeve 68 and passed through an upward bore 78 formed in the rear end of the lever 50, the head of the fastener 74 bearing against the underside of the lever 50. Accordingly, the finger engageable head 70 may be turned to adjustably angularly displace the lever 50 relative to the body 12 whereby the elevation of the forward terminal end of the lever 50 relative to the forward terminal end 20 of the slot 14 may be varied in accordance to the spacing of the eye 60 above the lower pointed terminal end of the needle 58.

One side surface 80 of the body 12 is provided with a longitudinal laterally outwardly opening slot 82 opening through the opposite ends of the body 12 and a lever 84 has its mid-portion pivotally anchored in the longitudinal mid-portion of the slot 82 by means of a pivot fastener 86. The rear end portion of the lever 84 is yieldingly biased laterally outwardly of the slot 82 by means of a coil spring 88 seated in a laterally outwardly opening blind bore 90 formed in the body 12 and opening outwardly of the side 80 thereof. The outer end of the compression spring 88 bears against the inner edge portion of the rear end of the lever 84 seated in the slot 80.

The forward end of the lever 84 includes a transversely directed beak 92 which is pointed and defines a cam surface 94 retracted to one side of the groove 44 in the manner illustrated in solid lines in FIG. 2 and projectable, upon angular displacement of the lever 84 from the solid line position thereof illustrated in FIG. 2 to the dotted line position illustrated in FIG. 2, into the slot 44 from the outer side thereof for the purpose of clamping the needle 58 in seated position within the groove 44.

In operation, and with the assumption that the lever 50 is properly adjusted so as to position the eye 60 in

registry with the forward terminal end 34 of the blade member 16 when the lower pointed end 56 of the needle 58 is abutted against the forward terminal end 54 of the lever 50, the rear end of the lever 84 is depressed inwardly against the biasing action of the spring 88 so as to retract the beak 92 to the solid line position thereof illustrated in FIG. 2. Then, with the blade member 16 retracted to the solid line position illustrated in FIG. 3 and the sewing machine thread 64 extending 10 through the groove 46, the forward end of the body 12 is advanced toward the needle 58 until the latter is seated in the groove 44. Thereafter, the body 12 is elevated until such time as the pointed lower terminal end 56 of the needle 58 abuts the upper surface of the forward terminal end 54 of the lever 50, at which point the eye 60 of the needle 58 will be in registry with the forward terminal end 34 of the blade member 16. Thereafter, the rear end portion of the lever 84 is released so that the lever 84 may swing from the solid line position 15 thereof illustrated in FIG. 2 to the dotted line position illustrated in FIG. 2 under the biasing action of the spring 78 with its beak 92 received in a third groove 100 formed in the body 12 above the groove 46, generally paralleling the groove 46 and also intersecting the groove 44. In this manner, the cam surface 94 will engage and clampingly seat the needle 58 in the groove 44. Then, manual pressure may be applied to the blade member 16 so as to forwardly advance the latter in order that the notched forward end edge 62 of the forward terminal end 34 thereof may be projected out of the forward end of the slot, engage the thread 64 and project the thread 64 through the eye 60 of the needle 58 in the manner illustrated in FIG. 4. Of course, the lever 50 may be adjusted in position so as to compensate for the eyes of various different needles being spaced differently from the pointed ends thereof. Also, it will be seen that the forward corners of the body 12 are sharply beveled as at 96 and 98 in order that the forward end of the body 12 may be closely positioned relative to a sewing machine needle without interference from any portion of the sewing machine needle support structure or pressure foot structure.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention.

What is claimed as new is as follows:

1. A needle threader for a sewing machine needle, said threader including body means defining a first elongated substantially straight and laterally outwardly opening groove, said body means including abutment means registered with one end of said groove and adjustably shiftable lengthwise thereof, said abutment means being adapted to have the pointed end of a needle seated in said groove abutted thereagainst for adjustably longitudinally positioning said needle in said groove, said body means also including means defining a second elongated substantially straight and laterally outwardly opening groove disposed at generally right angles relative to and including a longitudinal mid-portion intersecting with a longitudinal mid-portion of said first groove and with said first and second grooves opening laterally outwardly in substantially the same

direction, said direction disposed generally normal to said plane, and an elongated blade portion having one terminal end thereof, having major and minor cross-sectional dimensions disposed at generally right angles relative to each other, supported from said body for guided longitudinal oscillation back and forth transversely through the intersecting portions of said grooves along a path generally paralleling said direction, said terminal end being disposed with its major cross-sectional dimension extending along said first 10 groove for projection of said terminal end through the eye of a needle seated in said first groove, having its pointed end abutted against said abutment means and having its eye generally centered on said path, and cam means shiftably supported from said body for movement between a first retracted position to one side of said first groove and a second operative position extending across said first groove with a portion thereof projecting into said first groove from the open side thereof.

2. The combination of claim 1 wherein said abutment means comprises one end of an elongated lever generally paralleling said path and oscillatably supported, intermediate its opposite ends, from said body means for rocking about a transverse axis generally paralleling 25 said second groove, and adjustment means interconnected between said body means and the other end of said lever for adjustably shifting said other end relative to said body means.

10

15

20

30

40

45

50

55

60

65

3. The combination of claim 2 wherein said body means and said blade portion include coacting means establishing limits of oscillation of said blade portion relative to said body means.

4. The combination of claim 3 including thrust means operatively connected between said blade portion and said body means yieldingly biasing said blade portion toward its limit position with said terminal end retracted from said grooves.

5. The combination of claim 1 wherein said cam means includes a lever supported, intermediate its opposite ends, from said body for oscillation about an axis generally paralleling said first groove, one end portion of said lever including a laterally projecting beak defining a cam surface facing toward the other end of said lever and inclined relative to the direction in which said beak projects, said cam surface being swingable into position into engagement with the outer side of a needle seated in said first groove.

6. The combination in claim 5 wherein said body includes a third elongated substantially straight and laterally opening groove formed therein generally paralleling the second groove and disposed on the side thereof remote from said abutment means, said third groove intersecting, centrally intermediate its opposite ends with said first groove, said beak and cam surface being swingable into and out of said third groove.
